[57] CLAIM

The ornamental design for a combined tobacco smoking pipe bowl and receiving stem, as shown.

DESCRIPTION

FIG. 1 is a perspective view of the combined tobacco smoking pipe bowl and receiving stem in accordance with my design;

FIG. 2 is a front elevational view thereof with the rear view being a mirror image;

FIG. 3 is a top plan view thereof;

FIG. 4 is a right side elevational view thereof; and,

FIG. 5 is a bottom plan view thereof.

The undisclosed bottom portion of FIG. 4 is identical in appearance to the disclosed bottom of FIG. 2.
